UNITED STATES PATENT OFFICE.

JOSEPH P. LOTZER, OF KENT, MINNESOTA.

TRACE AND METHOD OF MAKING SAME.

Application filed April 2, 1923. Serial No. 629,436.

To all whom it may concern:

Be it known that I, JOSEPH P. LOTZER, citizen of the United States, resident of Kent, in the county of Wilkin and State of Minnesota, have invented certain new and useful Improvements in Traces and Methods of Making Same, of which the following is a specification.

This invention relates to improvements in traces and the method of making the same and particularly to traces composed of two or more parts adapted to be secured together to form a strong durable trace. Such traces are usually formed of leather 10 with added reinforcing parts secured, for example, by lines of stitching sewn through-and-through the parts and extending longitudinally of the traces and thus exposed to constant wear particularly on the side of the 15 trace adjacent the flank of the horse.

This invention is principally directed to the forming of a trace wherein exposure to wear of the securing means is minimized.

The object therefore of this invention is 20 to provide an improved trace and method of making the same.

Other objects of the invention will more fully appear from the following description and the accompanying drawings and will 25 be pointed out in the annexed claims.

In the accompanying drawings, there has been disclosed a structure designed to explain and to carry out the objects of the invention but it is to be understood that the 30 invention is not confined to the exact features shown as various changes may be made within the scope of the claims which follow.

In the drawings:

40 Figure 1 is a view in side elevation of the trace and portions of a hame;

Figure 2 is a cross-sectional view on the line 2-2 of Figure 1; and

45 Figure 3 is a view similar to that of Figure 2, but showing an intermediate step in the method of making the trace.

In this selected embodiment of the invention there is shown a trace composed of an elongated strip of material which is 50 folded longitudinally to produce an intermediate pocket within which is received an elongated reinforcing member shaped to be seated and longitudinally to extend within such pocket. The reinforcing member is held in assembled position by means of one or more lines of stitching extending through

the member and through one fold only of the covering strip and the member and both folds are held preferably by a single line of stitching with the result that the side 60 of the trace adjacent the flank of the horse has only a single line of stitching exposed to the constant wear thereby entailed.

The first step in the method of forming the novel trace is the provision of an elongated strip 4 of leather which is, as is indicated in Figure 3, in width a little more than twice the width of the completed trace. A reinforcing member 5 is then provided with a length substantially equal to that of the strip 4 and with a width slightly less than one-half that of the strip. This member 5 is preferably of leather although a strong durable fabric or other suitable material may be employed. The member 5 is 70 then positioned against one side face of the strip with one longitudinal edge of each in adjacency or preferably in transverse alignment. The member and strip are then stitched together preferably by two transversely spaced and longitudinal lines of through-and-through stitching 6 which are 75 preferably adjacent the edge portions of the member 5 as is suggested in Figure 3. The free portion or fold 7 of the strip is then 80 turned over the member 5. That is, the strip is longitudinally folded to assume a shape which is substantially U-shaped in cross-section to provide an intermediate pocket for the reinforcing member. After 85 so turning or folding the strip into the form shown in Figure 2, the two folds of the strip and the embraced member 5 are stitched together preferably by a single line 90 of through-and-through stitching. The outer face of the fold 7 thus presents a single line of stitching and this face may 95 become the inner face of the completed trace and thus positioned next to the flank of the horse. It may be noted that the single exposed line of stitching is preferably located adjacent the longitudinal edge portion of the completed trace at which portion the liability to engagement with the horse flank 100 is minimized and resultant wear reduced.

105 The completed trace is shown, in Figure 1, as provided at one end with the usual standard screw-cockeye 9 held to the trace by means of a common form of metallic strap-connection 11, while the other end 110 of the trace is shown connected to a hame 12 by a common form of attachment.

Having thus described my invention what I claim as new, and desire to secure by Letters-Patent, is:

1. The method of making a trace which 5 consists in providing an elongated outer strip and an elongated reinforcing strip of less width than the width of the outer strip, positioning the reinforcing strip against one face of the outer strip with one longitudinal edge of each strip in adjacency, 10 passing fastening means through the two strips to secure the two strips together, longitudinally folding the wider outer strip substantially to embrace the reinforcing strip 15 thereby covering said securing means on one trace side, and finally securing together the two folded portions of the outer strip and the embraced reinforcing strip.
2. The method of making a trace which 20 consists in providing an elongated outer strip and an elongated reinforcing strip of a width less than one-half of that of the outer strip, positioning the reinforcing strip against one face of the outer strip with one longitudinal edge of each strip in transverse alignment, securing the two strips together by spaced lines of through-and-through stitching, longitudinally folding the wider outer strip substantially to embrace the reinforcing strip thereby covering 25 said lines of stitching on one trace side, and finally securing together the two folded portions of the outer strip and the embraced reinforcing strip.
3. A trace comprising an elongated strip of material folded longitudinally to produce an intermediate pocket, an elongated 30 reinforcing member shaped to be seated and longitudinally to extend within said pocket, one fold of said strip to hold the strip and member in fixed position, and means to secure both strip folds and said member so that only the latter securing means is exposed to wear on one face of the 35 trace.
4. A trace comprising an elongated strip of material folded longitudinally to produce an intermediate pocket, an elongated reinforcing member shaped to be seated and longitudinally to extend within said pocket, a longitudinal line of stitches extending through-and-through said member and one fold of said strip, and a longitudinal line of stitches extending through-and-through both strip folds and member whereby only the latter stitches are exposed to wear on one face of said trace.
5. A trace comprising an elongated strip of material folded longitudinally to produce an intermediate pocket, an elongated reinforcing member shaped to be seated and longitudinally to extend within said pocket, a plurality of spaced longitudinal lines of stitches extending through-and-through said member and one fold of said strip, and a single longitudinal line of stitches extending through-and-through both strip folds and member whereby only the latter line of stitches is exposed to 60 wear on one face of said trace.

In witness whereof, I have hereunto set my hand this 29 day of March 1923.

JOSEPH P. LOTZER.
